No. 774,057.

PATENTED NOV. 1, 1904.

J. M. FAGAN.
BLOW-OFF MECHANISM.
APPLICATION FILED JULY 11, 1904.

NO MODEL.

UNITED STATES PATENT OFFICE.

JAMES MORRIS FAGAN, OF NEW YORK, N. Y.

BLOW-OFF MECHANISM.

SPECIFICATION forming part of Letters Patent No. 774,057, dated November 1, 1904.

Application filed July 11, 1904. Serial No. 216,052. (No model.)

To all whom it may concern:

Be it known that I, JAMES MORRIS FAGAN, a citizen of the United States, and a resident of the city of New York, borough of the Bronx, 5 in the county and State of New York, have invented a new and Improved Blow-Off Mechanism, of which the following is a full, clear, and exact description.

This invention relates to improvements in 10 blow-off mechanism or valves for steam-boilers, an object being to provide a blow-off of simple and novel construction so arranged that a main valve when closed will be submerged in clear water, thus reducing to a minimum 15 the danger of destroying the valve by the action of scale and sediment, and, further, to so place the valve that scale will not adhere to it when the device is in operation.

Other objects of the invention will appear 20 in the general description.

I will describe a blow-off mechanism embodying my invention and then point out the novel features in the appended claims.

Reference is to be had to the accompanying 25 drawings, forming a part of this specification, in which similar characters of reference indicate corresponding parts in all the figures.

Figure 1 is a side elevation of a blow-off mechanism embodying my invention, showing 30 the same as connected to a steam-boiler. Fig. 2 is a sectional elevation of the device. Fig. 3 is a section on the line $\alpha\alpha$ of Fig. 2. Fig. 4 is a sectional elevation showing a modification, and Fig. 5 is a side view showing 35 another modification.

Referring first to the example of my improvement shown in Figs. 1, 2, and 3, 1 designates a depending casing divided centrally by a partition 2, which at its lower end is 40 spaced from the casing, and this partition provides for two water-legs 3 4 in the casing. The leg 3 may be termed the "inlet" leg and the leg 4 the "outlet" leg. Communicating with the upper end of the leg 3 is a pipe 5, leading from the boiler, and extended from the upper end of the leg 4 is an outlet 6, which communicates with a sewer or other point of discharge.

Extended across the upper portion of the 45 inlet-leg 3 is a diaphragm having a vertical

wall 7, provided with a valve-seat 8, having a valve 9, the stem 10 of which extends outward through a suitable stuffing-box 11, which is screwed into a wall of the casing and is of sufficient size to permit the valve to be removed through the opening when necessary for repairs or the like.

Arranged in the upper portion of the outlet-leg 4 is a diaphragm having a vertical wall 12, provided with a valve-seat 13 for receiving a valve 14, the stem 15 of which extends outward through a stuffing-box 16. It will be seen that these valves 9 and 14 extend with their faces in substantially vertical position, so that water and sediment carried therewith 65 may pass freely through the valve-seat openings without any material portion of the sediment collecting on the valves or on the seats, thus not only prolonging the life of the valves, but making them practically water-tight.

Communicating at its top and bottom with the outlet-leg 4 is a glass sight-tube 17, through which the condition of the water in the casing may be observed.

In Fig. 4 the auxiliary valve 18 is designed 75 to engage in an opening formed in a diaphragm 19, arranged between the upper end of the leg 4 and the discharge-pipe 6, and in this instance the main valve 20 is arranged in a position similar to that of the valve 14 in 80 the first example described. In both cases, however, the main valve is located between the outlet and the inlet.

In Fig. 5 the water-legs are formed of a length of pipe 21 bent to a substantially U 85 shape, forming the inlet and outlet legs, and in the outlet-leg are valves 22 23, similar to the valves 18 and 20.

In the operation the main valve is to be opened wide and the inflow regulated by the auxiliary valve. In shutting off the flow the auxiliary valve is closed and some of the dirt and scale may be caught between the valve and its seat, which will not, however, cause sufficient leaking to prevent the operation of 95 the device or never enough to prevent the suspended matter in the water in the casing from settling to the lower end of it, leaving the main valve in clear water. As the valve and seat are clean and submerged in clear 100

liquid, they will come together tightly, insuring an absolutely tight joint. As before stated, the clearing of the water may be observed in the glass 17.

5 Having thus described my invention, I claim as new and desire to secure by Letters Patent—

1. A blow-off for steam-boilers, comprising a pair of communicating water-legs, a dia-
10 phragm in one of the legs having a vertical portion provided with a valve-seat, a valve for engaging in said seat, and a valve ar-
ranged between the first-named valve and the outlet of the device.

15 2. A blow-off for a steam-boiler, comprising a pair of water-legs communicating at the lower end, a main valve, and an auxiliary valve, the said valves having their faces ar-
ranged in vertical planes.

20 3. A blow-off for a steam-boiler, comprising vertically-disposed communicating water-legs, the said communication being at the lower end, an inlet-pipe leading into one of said legs, an outlet-pipe leading from the
25 other of said legs, a diaphragm in the upper portion of the inlet-leg and having a vertical portion provided with a valve-seat, a valve for engaging in said seat, a diaphragm at the

upper portion of said other leg and having a vertical portion provided with a valve-seat, 30 and a valve for engaging therein, the faces of said valves being disposed vertically.

4. A blow-off for a steam-boiler comprising a casing having a vertical partition spaced from the bottom of the casing and dividing 35 said casing into an inlet water-leg and an outlet water-leg, an auxiliary valve arranged at the upper portion of the inlet water-leg, a main valve arranged at the upper portion of the outlet water-leg, and a sight-tube com- 40 municating at its ends with said outlet-leg.

5. A blow-off for a steam-boiler, comprising a pair of water-legs communicating at the lower end, a main valve, an auxiliary valve, the said valves having their faces arranged in 45 vertical planes, and a sight-tube communicat-
ing at its upper and lower ends with one of the water-legs.

In testimony whereof I have signed my name to this specification in the presence of two sub- 50 scribing witnesses.

JAMES MORRIS FAGAN.
